UNITARY OUTER SKIRT AND GIRDLE

Sol J. Rosenberg, Whitefish Bay, Wis., assignor to Junior House, Inc., Milwaukee, Wis., a corporation of Wisconsin

Application June 23, 1948, Serial No. 147,141

Term of patent 7 years

(Cl. D3—26)

To all whom it may concern:

Be it known that I, Sol J. Rosenberg, a citizen of the United States, residing at Whitefish Bay, in the county of Milwaukee and State of Wisconsin, have invented a new, original, and ornamental Design for Unitary Outer Skirt and Girdle, of which the following is a description, reference being had to the accompanying drawing, forming a part thereof.

In the drawing:

Fig. 1 is a front perspective view of a unitary outer skirt and girdle embodying my new design; and

Fig. 2 is a rear and side perspective view of the unitary skirt and girdle.

I claim:

The ornamental design for a unitary outer skirt and girdle, substantially as shown.

SOL J. ROSENBERG.
